United States Patent Office

Des. 175,722
Patented Oct. 4, 1955

175,722

BOX

Elizabeth Nightingale Graham, New York, N. Y.

Application December 16, 1954, Serial No. 33,588

Term of patent 14 years

(Cl. D58—13)

The top and side portions of the design shown in the drawing are lined to represent the color gold.

I claim:

The ornamental design for a box, substantially as shown and described.
